P. DEVARCO.
REVERSIBLE BROOM AND THE LIKE.
APPLICATION FILED MAY 10, 1919.

1,345,353.

Patented July 6, 1920.

UNITED STATES PATENT OFFICE.

PAUL DEVARCO, OF WEST HOBOKEN, NEW JERSEY.

REVERSIBLE BROOM AND THE LIKE.

1,345,353.

Specification of Letters Patent.

Patented July 6, 1920.

Application filed May 10, 1919. Serial No. 296,070.

To all whom it may concern:

Be it known that I, PAUL DEVARCO, a citizen of the United States, and residing at West Hoboken, in the county of Hudson and State of New Jersey, have invented certain new and useful Improvements in Reversible Brooms and the like, of which the following is a specification, such as will enable those skilled in the art to which it appertains to make and use the same.

This invention relates to brooms, brushes, mops and like articles, and the object of the invention is to provide a reversible article of this class which is simple in construction and operation and efficient in use, and which comprises a frame construction with which brush, broom or mop material may be detachably connected; and with this and other objects in view the invention consists 20 in a device of the class specified, constructed and operated as hereinafter described and claimed.

The invention is fully disclosed in the following specification, of which the accompanying drawing forms a part, in which the separate parts of my improvement are designated by suitable reference characters in each of the views, and in which:—

Figure 1 is a side view illustrating one 30 use of my improvement;

Fig. 2 a partial section on the line 2—2 of Fig. 1 and on an enlarged scale;

Fig. 3 a partial section on the line 3—3 of Fig. 2; and

Fig. 4 a perspective view of one end portion of one of a number of clamp plates which I employ.

In Fig. 1 of the drawing, I have shown at 5 my improved frame which comprises a yoke-shaped frame member 6 preferably composed of heavy spring wire and centrally of the cross head of said frame member is secured a T-shaped coupling 7 with which a wooden or other handle rod 8 is connected. The side arms 9 of the yoke-shaped frame member 6 are provided at a predetermined distance from their ends with collars 10, and mounted on said end portions of the arms 9 is a clamp head 11, 45 held in place by milled nuts 12.

The clamp head 11 comprises substantially L-shaped sides, the parts 14 of said sides being connected by a transverse plate

15 by riveting or otherwise, as shown at 16 in Fig. 2 of the drawing, and the other parts 17 of the sides 13 are provided centrally with vertically arranged bead or sleeve portions 18 pressed or stamped from the parts 17 and through which the end portions of the arms 9 pass, as clearly shown in Figs. 1 and 2.

The transverse plate 15 comprises a back 19 having a central V-shaped portion 20 and the opposite sides of the back 19 are bent at right angles to form flanges 21 as clearly shown in Fig. 3 of the drawing. In practice, I preferably employ a plurality of other plates 22, a detail view of a part of one of which is shown in Fig. 4, and are of the same form and construction as the plate 15, but which are independent of said plate and the sides 13 of the clamp head 11, and are adapted to be detachably connected with said head.

The plates 22 consist of backs 23 having 75 central V-shaped portions 24, and the side edges of said plates are provided with flanges 25 bent at right angles to the backs 23, and the plates 22 as well as the plate 15 are provided at predetermined intervals 80 and in common alinement with apertures 26, four of which are preferably employed in each plate in the construction shown, and through which four bolts 27 are adapted to pass. The bolts 27 are provided at 85 one end with heads 28 and at the opposite or threaded end thereof, the bolts are pointed as shown at 29 and winged nuts 30 are mounted on said threaded ends. Washers 31 are preferably placed between 90 the heads 28 of the bolts and the plate 15, said washers being provided with beveled sides 32 which permit said washers to fit snugly within the V-shaped central portion 20 of the plate 15, as clearly shown in Figs. 95 2 and 3. Other washers 33 are also preferably employed between the winged nuts 30 and the outer plate 24, the inner faces of said washers being made V-shaped in form as shown at 34 in Fig. 3 to fit snugly over 100 the central V-shaped portion 24 of the outer plate 22.

In the use of the device it will be understood that the L-shaped sides 13 are connected by the plate 15 and form the frame 105 of the clamp head 11, while the other plates

22 are mounted on and movable longitudinally of the bolts 27, within the sides 13. In the accompanying drawing I have shown a plurality of two-faced brush or broom members 35, three of which are shown, and these brush members are secured to or held in place between the plates 15—22 by the bolts 27, as shown in Figs. 2 and 3 of the drawing, the bolts 27 being passed through 10 the central portions of the brush members 35, and said central portions being clamped between said plates which securely holds the same in place.

As shown in Fig. 1 of the drawing, the 15 faces 36 of the brush or broom members 35 are directed downwardly and are in position for use, while the opposite faces 37 are directed upwardly and when the faces 36 of said members become worn, the opposite 20 site faces thereof may be moved downwardly, or the device reversed by loosening the milled nuts 12 on the arms 9 and withdrawing said arms from the beaded or sleeve portions 18 of the sides 13 and again 25 passing said arms through said beaded or sleeve portions 18 in the opposite direction or with the faces 37 directed downwardly, and again placing the milled nuts 12 in position. It will be seen that in this operation 30 it will not be necessary to remove the brush or broom members 35, but it will be apparent that when both of the faces 36—37 of the brush or broom members 35 have become worn and useless other members may 35 be substituted for the old members by removing the winged nuts 30 on the bolts 27 as well as the washers 33 and withdrawing the plates 22 from said bolts.

While I have shown and described my 40 improvement as designed to hold brush or broom material, it will be understood that straw, hair, bristles, wire or fibrous material of any kind or class may be employed in connection with the clamp head 11, or 45 any combination of materials such as above specified may be employed. In other words, one face of the broom may be provided, or may consist of straw material, while the other may consist of hair, wire or other material, and with this device, after a purchaser has procured a frame with a number of the brush members 35 therein, other brush members may be procured and used in the same frame and in this way the brush 55 may be repaired, or a practically new brush made whenever necessary or desirable, and with a frame constructed in the manner above set out, I produce a broom, brush or the like which will have more or less spring 60 qualities by reason of the yoke-shaped frame member 6, and this will aid or facilitate the use of the device. It will also be apparent that while I have shown certain details for carrying my invention into effect, I am not 65 necessarily limited to these details, and vari-

ous changes therein and modifications thereof may be made, within the scope of the appended claims, without departing from the spirit of my invention or sacrificing its advantages.

70

Having fully described my invention, what I claim as new and desire to secure by Letters Patent, is:—

1. A device of the class described comprising a yoke-shaped frame provided centrally of the cross head thereof with a handle member, a clamp head detachably connected with the free end portions of said frame and comprising side members connected by a plate member, the free ends of said yoke-shaped frame being adapted to pass through and detachably secured to said side members, other plate members mounted between the side members of the clamp head, and bolts passed through all of said plate members 85 and adapted to secure brush or similar material between said plate members.

2. A device of the class described comprising a clamp head having a plurality of independent plate members between which brush or similar material extending in opposite directions from said clamp head is adapted to be secured, bolts passed through said plate members to draw the same together and secure the brush or other material therebetween, end plates on one of the plate members of said clamp head and adapted to inclose the opposite end portions of said clamp head, and a handle frame detachably and reversibly connected with the end plates of said clamp head.

3. A reversible device of the class described comprising a yoke-shaped frame, a clamp head comprising a plurality of plate members provided with V-shaped portions 105 and at the opposite sides thereof with flanged portions, said plate members being placed one upon another with the flanged and V-shaped portions extending in one direction and with brush material between 110 the adjacent faces thereof, means for securing said plate members together and for clamping said brush material therebetween, plates secured to the end portions of one of said plate members and adapted to inclose 115 the opposite end portions of said clamp head, said plates being provided with cylindrical portions, and a yoke-shaped handle frame detachably and reversibly connected with the cylindrical portions of said plates. 120

4. A reversible device of the class described comprising a yoke-shaped frame, a clamp head detachably and reversibly connected with said frame, said clamp head comprising a plurality of sheet metal plate 125 members provided centrally with V-shaped portions and at the opposite sides thereof with flanged portions extending in the same direction as said V-shaped portions, bolts passed through said plate members for 130

drawing the same together to secure brush
or similar material therebetween, and means
at the ends of said plate members for mount-
ing said yoke-shaped frame in connection
therewith.

In testimony that I claim the foregoing
as my invention I have signed my name in

presence of the subscribing witnesses this
8th day of May, 1919.

PAUL DEVARCO.
